DISPLAY STAND FOR A GOLF BALL OR THE LIKE

Evans G. Davis, Heilwood, Pa. 15745

Filed Aug. 4, 1967, Ser. No. 8,143

Term of patent 7 years

U.S. Cl. D80—9
Int. Cl. D20—02

The figure is a perspective view of a display stand for a golf ball or the like showing my new design.

The broken line representation of a golf ball is for purposes of illustration only.

I claim:

The ornamental design for a display stand for a golf ball or the like, as shown and described.
